UNITED STATES PATENT OFFICE.

ROBERT JACKSON GARISON, OF HASTINGS, OKLAHOMA.

PAN-LIFTER.

1,346,820.

Specification of Letters Patent. Patented July 20, 1920.

Application filed November 3, 1919. Serial No. 335,398.

To all whom it may concern:

Be it known that I, ROBERT J. GARISON, a citizen of the United States, residing at Hastings, in the county of Jefferson and State of Oklahoma, have invented a new and useful Pan-Lifter, of which the following is a specification.

This invention relates to kitchen articles and more particularly to devices known in the art as plate lifters.

The primary object of the invention is to provide a device of this character having opposed lifting sections, the sections being so constructed that the same may be adjusted to permit its use in connection with pans, or plates, of various diameters.

A still further object of the invention is to provide means for operating the lifting sections, the means being located adjacent the thumb of the operator, to permit the lifting sections to be manipulated when supported by one hand of the operator.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:—

Figure 1 illustrates an end elevational view of the plate lifter, showing its relation with the plate, when in actual use, the plate being illustrated by dotted lines.

Fig. 2 illustrates a side elevational view of the same, the plate and handle being shown as partly broken away.

Fig. 3 illustrates a fragmental end elevational view of the device, and

Fig. 4 illustrates a detail view partly in section, disclosing the connection between the operating lever, and the body of the lifter.

Referring to the drawing in detail, the reference character 5 designates body of the lifter, which includes a relatively long rod, apertured at one end, as at 6, the opposite end thereof being provided with the handle 7.

A slot 8 is formed in the body of the lifter, and receives the extension 9, formed on the operating lever 10, the pivot pin 11,

being shown as passing through the side walls of the slot 8, and supporting the operating lever in proper relation with the body of the device, the pivot pin 11 forming the support to permit free movement of the operating lever with relation to the body 5.

A tubular member 12, is supported on the body 5, one end of said tubular member 12, being disposed adjacent the outer or free end of the body 5, and provides a shoulder for purposes to be hereinafter more fully described.

The opposite end 13, of said tubular member 12, is disposed in spaced relation with the slot 8. The clamping sections are supported on the body 5, to have a free pivotal movement with relation thereto, the pivotal movement being accomplished by manipulation of the operating lever 10, which has connection with the clamping sections 75 through the medium of the arm 14, and the links 15 and 16, the upper end of the links being curved as at 17, and passing through suitable openings in the arm 14, the opposite ends thereof being hooked as at 18, the 80 hooked portions being disposed within the openings 19 of the arms of the clamping section.

Each of these clamping sections includes a pair of opposed relatively wide members 20, having a plurality of apertures 20' disposed therein, in spaced relation with each other, the ends of the respective members 20, extending inwardly as at 21 and formed with an aperture 22.

The plate engaging portion of each clamping section, includes a length of wire bent intermediate its length to provide a curved portion 23, which extends inwardly toward the body 5, as at 24, to provide a shoulder, 95 equal to the width of the ordinary baking pan, or plate, now in use, the arms of said plate engaging portions passing through the openings 22, the extreme ends thereof extending at right angles to the arms, as at 100 25, and as shown, are positioned within predetermined openings formed in the relatively wide members 20, the inner extremities of each of the relatively wide members 20, is apertured as at 26, to permit the same 105 to be supported on the body 5 of the lifter, the shoulders formed adjacent the ends of the tubular member 12, preventing longitudinal movement of the members 20, with relation to the body 5, in one direction, the 110

pins 27, which pass through the body 5, engage the members 20, and prevent movement of the members with relation to the body, in the opposite direction.

5 From the foregoing it will be seen that when it is desired to lift a plate from a stove or oven, it is only necessary to press the lever 10, to cause the clamping sections to move to the limit of their outward movement, whereupon the same are dropped over the edges of the pan.

It follows that the plate lifter may now be raised, with the result that the shoulders 24 tightly grip the usual flange of a pan, 15 and permit the same to be moved to any predetermined position.

To release the lifter from the pan, the lever 10 is again operated to extend the clamping sections to the limit of their outward movement, which releases the shoulders 24 and the lifter is now free from the pan, which has been moved thereby.

Having thus described the invention, what is claimed is:

- 25 1. In a pan lifter, an elongated body portion, opposed clamping sections pivotally supported on the body, each of the clamping sections having a series of openings formed therein, plate engaging portions 30 having their ends disposed in predetermined openings of the apertured members, and means for operating the clamping sections to cause the same to move toward and away from each other.
- 35 2. In a pan lifter, a body portion, opposed clamping sections, each of the clamping sections including apertured members, and plate engaging members, means for adjusting the plate engaging members with relation to the apertured members, to permit the device to be employed with various sized plates, a lever mechanism having connection with the clamping sections, whereby movement of the lever mechanism causes a 40 relative movement of the clamping sections.
- 45

for moving the clamping sections toward and away from each other.

3. In a pan lifter, a body, a handle formed on one end of the body, clamping sections pivotally connected on the body, an operating lever pivotally supported on the body and having a portion thereof extending to a point over the handle, means for connecting the operating lever to the clamping sections, and means for adjusting the clamping sections laterally.

4. In a pan lifter, a body portion, clamping sections pivotally supported on the body portion, each of said clamping sections including apertured members, each of said apertured members having an inturned apertured end, a plate engaging member forming a part of each clamping section, each plate engaging member including spaced arms disposed within the openings of the inturned ends of the apertured members, and means carried by each of the plate engaging members for co-operating with the apertures of the apertured members for permitting adjustment of the plate engaging members with relation to the apertured members, and means for operating the clamping sections.

5. In a pan lifter, a body, a tubular member disposed on the body, clamping sections having connection with the body adjacent the ends of the tubular member, said clamping sections including plate engaging portions, means for permitting adjustment of the plate engaging sections laterally, with relation to the body, and means for operating the clamping sections.

In testimony that I claim the foregoing as my own, I have hereto affixed my signature in the presence of two witnesses.

ROBERT JACKSON GARISON.
